UNITED STATES PATENT OFFICE.

JONAS W. AYLSWORTH, OF EAST ORANGE, NEW JERSEY, ASSIGNOR TO NEW JERSEY PATENT COMPANY, OF WEST ORANGE, NEW JERSEY, A CORPORATION OF NEW JERSEY.

APPARATUS FOR PRODUCING DUPLICATE SOUND-RECORDS.

1,071,685.

Specification of Letters Patent.

Patented Sept. 2, 1913.

Original application filed April 29, 1909, Serial No. 493,052. Divided and this application filed January 20, 1911. Serial No. 603,677.

To all whom it may concern:

Be it known that I, JONAS W. AYLSWORTH, a citizen of the United States, and a resident of East Orange, Essex county, New Jersey, have invented a certain new and useful Apparatus for Producing Duplicate Sound-Records, of which the following is a description.

My invention relates to apparatus for producing duplicate sound records, this application being a division of my application entitled method of and apparatus for producing duplicate sound records, Serial No. 493,052, filed April 29, 1909.

My object is to provide means for molding disk sound records by the well known centrifugal or spinning process, the means disclosed and claimed being well adapted for carrying out the process claimed in my parent application above referred to.

Other objects of my invention reside in the combinations of parts and details of construction of the improved apparatus, all as described hereinafter and set forth in the appended claims.

Attention is hereby directed to the accompanying drawings forming part of this specification, and in which—

Figure 1 is an end elevation partly in section of one form of apparatus for carrying into effect my improved process. Fig. 2 is a longitudinal cross section through the same apparatus taken on line 2—2 of Fig. 1. Fig. 3 is an end elevation, partly in section, of a different form of apparatus. Fig. 4 is a partial plan view of the apparatus shown in Fig. 3, and Fig. 5 is a detail of construction of a modified form of mold to be employed in connection with the apparatus shown in Fig. 3.

My process consists broadly in rotating at high speed a hot disk record mold containing the molten or fluid record material in a circle to which the record surface of the mold is a tangent at its central point. By this means the material will be compressed by the centrifugal force developed against the record surface of the mold and be uniformly distributed thereover. A plurality of these molds may be secured to the sides of a symmetrical many-sided rotatable structure, or to the bore of a barrel-like structure which is rotated about an axis

from which all of the molds are equally distant. Generally speaking, the invention thus broadly defined has two specific forms. The molds may be open on the side toward the axis of rotation, in which case the material in molten or fluid condition may be introduced into the same and distributed evenly among the same during the rotation of the apparatus. Or secondly, an apparatus may be employed containing molds in the form of boxes having covers or closures. In such a process and apparatus, the material can be placed in solid or granular condition in each mold in turn, and the cover secured in place on the same before the apparatus is put into rotation. Or if a tight joint is obtained between the cover and the mold, the same method could be carried out in the case of the fluid or molten record material. Different advantages of each method and form of construction will be pointed out in connection with the description of the same.

Referring to Figs. 1 and 2 of the drawings, the polygonal frame 1 is supported by means of the standard 2 rising from the bed plate 3. The molds 4 are detachably secured in place to the sides of the polygonal frame 1, the said sides of the frame being recessed to allow the molds to fit therein. The molds are box-like, having bottoms 5 on the inner side of which is formed the matrix in relief, from which the record impression is to be taken, the molds also being formed with sides 6 and with flanges 7 resting on the outer surface of the sides of the polygonal figure. The molds may be secured in place in any desired manner, as by bolting or clamping or otherwise securing the molds to the frame by means of the mold flanges. The polygonal frame 1 may be an integral structure if desired, or may be formed of separable sides joined together as shown at the lines 1'. In this case the molds could, if desired, be permanently secured to the sides of the frame.

Material in molten or fluid condition is supplied to the various molds by means of the axial horizontal conduit 8. Molten or fluid material of a quantity determined to be sufficient for forming the records in the various molds is introduced or forced into the conduit 8 while the apparatus is in rapid ro-

tation, the apparatus being rotated by means of the application of any desired form of power to the hub 9 of the apparatus. The material fed into the conduit 8 passes thence into the radial tubes 10 whence it passes into preferably there is one radial tube 10 for the various molds. The radial tubes 10 rotate synchronously with the molds 4, and each mold. The tubes 10 might be allowed to deliver their molten material each one directly into its own particular mold, but owing to the difficulty of properly adjusting the supply of fluid material to each mold by this method, it is thought advisable to also furnish means for distributing and regulating the supply of the record material among the different molds. For this purpose the annular distributing ring 11 is used. This ring is supported in position to receive the record material from the ends of all the radial tubes 10 together with which it rotates. The record material supplied by the tubes 10 to the ring 11 passes thence into the various molds through passages as 12 provided in any suitable arrangement in the outer surface of ring 11 and leading into the molds. As soon as any mold has become filled, the molten or fluid material introduced into the ring 11 flows past the same to the next mold, whereby each mold becomes quickly filled with the record material. This material is compressed into contact with the record surface of the mold by the centrifugal force developed and may become solidified thereupon by cooling or evaporation or by chemical action, or in any other desired manner. If desired, means for cooling the molds after the proper time interval may be furnished. When the records have become sufficiently solidified, the machine may be stopped, the molds removed therefrom and the records then extracted from the molds. The record so formed will have a concave surface on the side opposite from the record surface, due to the manner in which they were formed. The amount of this concavity will be slight if the apparatus used is of sufficiently great diameter. Records so formed may be planed or milled or otherwise machined to make the rear surface parallel to the front or record surface, or the concavity on the rear side of the record can be filled up in any convenient manner as with plaster of Paris to make a straight surface, or a detachable piece can be used to fill the concavity when the record is placed on the turn table of the phonograph playing the same, or if desired, the record could be left with the under surface in its concave condition and the record used in connection with a phonograph have a convex turn table upon which the record fits.

It may be found desirable to supply heat to the record material in its passage through

the tubes 10 to the ring 11 in order to prevent congealing of the material in these passages. This heat may be supplied in any convenient manner, as by supplying hot air or gas through the conduit 11 to the record material, or in any suitable manner. In Figs. 1 and 2 I have shown an electric insulated heating coil 13 wrapped continuously around the various tubes 10 and the ring 11. As shown in Fig. 2, current may be led into the apparatus to this heating coil from any convenient source of power by means of the brush 14 which bears upon the conducting ring 15 of brass or any other convenient material, which ring is supported by the insulator 16 carried by the hub 9 of the apparatus. The other end of the conductor 13 is connected to the conducting ring 17 similarly supported by insulating ring 16, and from this ring 17, the current is led away by a brush 18 to the ground or the opposite side of the source of current. With such means the amount of heat to be supplied to the record material in its passage to the molds may be regulated to any desired amount.

The process and apparatus thus far described may be used in connection with any suitable record material of the usual wax-like or metallic soap composition, shellacs, and the like. Also, substances which may be affected by oxidation of the air while in a molten or plastic state may be molded in the apparatus shown by means of a process described in my application Serial No. 493,054, filed on Apr. 29, 1909. For this process, the frame 1 must be air tight, the air being exhausted from the interior of the same, and the record molded in a vacuum or other non-oxidizing or reducing atmosphere. By this method, sound records may be molded from such materials as metals, metallic alloys, glass-like compositions, shellac and shellac compositions, etc. Also, sound records may be molded by the process and in the apparatus here described of substances which in their final stage are non-plastic at such temperatures as may be used without injury to the substance or the matrix, such substances being mentioned, and processes for molding the same described in my applications Serial Nos. 493,258, and 493,416, filed May 1, 1909. In such processes, the desired material as phenols, etc., albumenoids, caseins, or other bodies which react with formaldehyde or equivalent agent in the desired manner, may be introduced into the molds with or without a suitable catalytic or condensing agent, and the formaldehyde or equivalent agent introduced from the conduit 8 either under normal or advanced pressure. Or the phenol or equivalent agent may be mixed with the formaldehyde or equivalent before the introduction of the resulting product into the

5 molds, in which case, if desired compressed air or other gas could be introduced through the conduit 8 to aid in the production of the records. In either case, the final reaction ensues in the molds by which the final non-plastic substance is formed in the molds by 10 polymerization or equivalent hardening process. For aiding in this final action, heat may be applied to the molds in their rotation in any convenient manner, as by 15 means of the burners 19.

10 Referring to Figs. 3 and 4, the molds 4 are represented as carried by the frame 1 in the same manner as described in connection 15 with Figs. 1 and 2. In this case, however, the molds 4 are provided with covers or closures 20 which may be screwed or otherwise closely secured within the mold 4, closing the open or inner side thereof. 20 The material may be placed in each mold, in solid or granular condition, before the cover is placed thereon or if desired, the cover 20 could first be secured in position and the material introduced within the mold 25 through a suitable valve 29 (see Fig. 5) placed in the cover, or elsewhere. I prefer to form the covers 20 with hollow radial projections or wells 21 for containing excess material. By this means, the mold 4 will 30 be entirely filled with molten material, the plane surface of the inner side of cover 20, forming the inner side of the record in a plane parallel to the record surface, the well 21 being partly filled with fluid material, the inner surface of the mold in this 35 well alone being given a curved formation due to the centrifugal action. After the hardening and removal of the record, the boss of surplus material formed by the well 21 may be removed.

40 If the material is introduced into the mold in solid or granular condition, the same may be melted by the heat of the mold into which it is introduced, or by heating 45 the molds during their rotation, as by burners 19, to which gas may be introduced as by means of the pipe 22. The apparatus in this case is represented as being rotatable upon the shaft 23. When it is desired to 50 further exhaust the air from the interior of the molding apparatus, the shaft 23 may be made hollow and the pipe 24 may pass axially therethrough. When it is desired to use an apparatus of the sort here 55 described having closed molds in a process in which air or gas should have free access to the record material in the mold, or when the material in the mold should be subjected to a vacuum, a mold such as that illustrated in Fig. 5 may be used. Here, the hollow boss 21 is provided with a central aperture 25 forming a valve seat adapted to be closed by the valve 26, which is tightly held in contact with its seat as by means 60 of the spring 27. When, however, the ap-

paratus has been rotated up to a certain speed sufficient to prevent the loss of any of the contents of the mold through the aperture 25, the centrifugal force acting on the valve 26 and the weight 28 connected therewith will overcome the tension of the spring 27, lifting the valve 26 from its seat, and giving free access to the air or gases used in the process to the record material in the mold.

75 The molds 4 shown in the various figures may be secured to the frame of the apparatus in any simple manner by which the same may be quickly and easily adjusted and removed, and the interior of the device 80 rendered accessible. For example, the frames containing the various molds can readily be secured in position across the peripheries of two concentric end pieces in the same manner that barrel staves are applied to the 85 ends of a barrel.

Having now described my invention, what I claim and desire to protect by Letters Patent is as follows:

1. In apparatus for forming disk sound 90 records centrifugally, in combination, a rotatable body, means for rotating the same about a center, a disk sound record mold affixed to the body at a distance from the center and at right angles to the radius, and 95 means for heating said mold during the rotation thereof, substantially as described.

2. In apparatus for forming disk sound records centrifugally, in combination, a rotatable body, means for rotating the same 100 about a center, and a disk sound record mold affixed to the body at a distance from the center and at right angles to the radius, means for introducing molten or fluid material therein, and means for heating said 105 introducing means, substantially as described.

3. In apparatus for forming disk sound records centrifugally, in combination, a rotatable body, means for rotating the same 110 about a center, a plurality of disk sound record molds affixed to the body at equal distances from the center and at right angles to the radii, means for introducing molten or fluid material therein while the body is rotating, and means for heating said introducing 115 means, substantially as described.

4. In apparatus for forming disk sound records centrifugally, in combination, a rotatable body, means for rotating the same 120 about a center, a plurality of disk sound record molds affixed to the body at equal distances from the center and at right angles to the radii, means for introducing molten or fluid material therein while the body is 125 rotating, and uniformly distributing the same among the various molds, and means for heating said introducing and distributing means, substantially as described.

5. In apparatus for forming disk sound 130

records centrifugally, in combination, a rotatable body, means for rotating the same about a center, a plurality of disk sound record molds affixed to the body at equal distances from the center and at right angles to the radii, means rotating with the body for introducing the molten or fluid material into the molds while the same are rotating, and uniformly distributing the same, and 10 means for heating said molds during the rotation thereof, substantially as described.

6. In apparatus for forming disk sound records centrifugally, in combination, a rotatable body, means for rotating the same 15 about a center, a plurality of disk sound record molds affixed to the body at equal distances from the center and at right angles to the radii, a number of radially arranged pipes rotating with the body for introducing 20 the molten or fluid material into the molds while the same are rotating, and a rotating annular conduit communicating with the outer ends of said pipes and also

communicating directly with said molds for distributing overflow from any mold among 25 the other molds, substantially as described.

7. In apparatus for forming disk sound records centrifugally, in combination, a rotatable body, means for rotating the same about a center, a plurality of disk sound 30 record molds affixed to the body at equal distances from the center and at right angles to the radii, and means rotating with the body for introducing the molten or fluid material into the molds while the same are 35 rotating and uniformly distributing the same, and means for heating the material-introducing means, substantially as described.

Correction in Letters Patent No. 1,071,685.

It is hereby certified that in Letters Patent No. 1,071,685, granted September 2, 1913, upon the application of Jonas W. Aylsworth, of East Orange, New Jersey, for an improvement in "Apparatus for Producing Duplicate Sound-Records," an error appears in the printed specification requiring correction as follows: Page 2, strike out line 6, and line 8, as now numbered, after the word "and" insert the words *preferably there is one radial tube 10 for*; and that the said Letters Patent should be read with this correction therein that the same may conform to the record of the case in the Patent Office.

Signed and sealed this 7th day of October, A. D., 1913.
